(57) **CLAIM**

A new original design for a universal tool handle, as shown and described herein.

DESCRIPTION

FIG. 1 is a front elevation view of a universal tool handle embodying our new design;

FIG. 2 is a rear elevation view thereof;

FIG. 3 is a right elevation view thereof;

FIG. 4 is a left elevation view thereof;

FIG. 5 is a top plan view thereof;

FIG. 6 is a bottom plan view thereof;

FIG. 7 is an isometric elevation view thereof;

FIG. 8 is a front elevation view of a second embodiment of the universal tool handle embodying our new design;

FIG. 9 is a rear elevation view thereof;

FIG. 10 is a right elevation view thereof;

FIG. 11 is a left elevation view thereof;

FIG. 12 is a top plan view thereof;

FIG. 13 is a bottom plan view thereof; and,

FIG. 14 is an isometric elevation view thereof;

The phantom and/or broken lines are for illustrative purposes only and form no part of the claimed design.
